FIG. 5

UNITED STATES PATENT AND TRADEMARK OFFICE
CERTIFICATE OF CORRECTION

PATENT NO. : D606,306 S
APPLICATION NO. : 29/288097
DATED : December 22, 2009
INVENTOR(S) : Bisson

Page 1 of 1

It is certified that error appears in the above-identified patent and that said Letters Patent is hereby corrected as shown below:

On the title page item (76), the name of the inventor should be "Montgomery Bisson" instead of Bisson Monte and his correct address is "19815 Windjammer Lane" instead of 1815 Windjammer Lane.

Signed and Sealed this
Twenty-sixth Day of March, 2013

Teresa Stanek Rea
Acting Director of the United States Patent and Trademark Office
